RAILWAY SIGNALING SYSTEM

Ralph R. Kemmerer, Swissvale, Pa., assignor to
The Union Switch & Signal Company, Swiss-
vale, Pa., a corporation of Pennsylvania

Application December 28, 1940, Serial No. 372,027

11 Claims. (Cl. 246—33)

My invention relates to a railway signaling system of the double overlap type adapted for use on a stretch of railroad track over which trains normally move in both directions. The system includes wayside signals which are controlled over line wires which parallel the track stretch.

It is an object of my invention to provide an improved signaling system of the type described which is arranged so that the number of line wires required is reduced to the smallest possible number.

A further object of my invention is to provide a signaling system of the type described which is arranged to reduce to a minimum the possibility that a signal will falsely display a proceed indication in the event there is a cross between the line wires.

Another object of my invention is to provide new and improved means for overlapping the control of the signals in a track stretch and for approach controlling the circuits of the lamps of these signals.

A further object of my invention is to provide a signaling system employing signals of the semaphore type, the system incorporating improved means for energizing the holding coils which are employed in signals of this type.

A further object of my invention is to provide an improved railway signaling system.

Other objects of the invention and features of novelty will be apparent from the following description taken in connection with the accompanying drawings.

I shall describe three forms of railway signaling systems embodying my invention, and shall then point out the novel features thereof in claims.

In the drawings Figs. 1, 1a and 1b taken together form a diagram showing a track stretch equipped with signaling apparatus embodying my invention.

Fig. 2 is a fragmentary view showing a modification which I may employ, and

Figs. 3, 3a and 3b taken together form a diagram showing a track stretch equipped with another form of signaling system provided by my invention.

Referring to Figs. 1, 1a and 1b of the drawings, there is shown therein a stretch of railroad track having track rails 1 and 2 over which traffic moves in both directions. The track rails are divided by insulated joints into track sections in the customary manner. To facilitate description of the equipment it will be assumed that the left-hand end thereof is west and that the right-

hand end thereof is east. Accordingly train movements from right to left are westbound and train movements from left to right are eastbound.

5 The track stretch includes passing sidings which are located at appropriate intervals and permit traffic to be diverted from the main track under the customary control of switches, not shown. Two such passing sidings are shown and are designated M and N.

The equipment associated with each of the passing sidings is the same as that associated with the other sidings, while the equipment for the track stretches between sidings is similar.

15 For purposes of explanation of the operation of the equipment the signals have been numbered starting from a point at the east end of each passing siding. The signals governing westbound traffic are identified by odd numbers, while the signals governing eastbound traffic are identified by even numbers. The signals starting at the east end of passing siding N are numbered in a series beginning with 1W, while the signals starting at the east end of passing siding M are numbered in a series starting with 21W. The reference characters for the westbound signals include the suffix W, while the reference characters for the eastbound signals include the suffix E. The track sections are numbered 1T, 2T, 3T, etc., in a series corresponding to that of the signals.

25 The signals are shown as being of the color light type, while each of the signals has associated therewith a suitable source of energy the terminals of which are designated (+) and (—) in the drawings. While color light signals are shown the invention is not limited to the use of signals of this type and any desired form of signals may be employed.

30 40 Each of the track sections is provided with a track circuit including a track battery connected across the section rails at one end of the section, and a track relay, designated TR with a suitable prefix, connected across the section rails at the other end of the section.

45 For the purpose of controlling the signals a number of line circuits are provided which are controlled by contacts of the track relays. These line circuits are employed to determine the indications displayed by the signals and also to govern lighting of the lamps of the signals.

50 55 In order that the same line circuits may be employed to control both the east and the westbound signals means is provided for supplying alternating current energy to certain of these

line circuits at one end, and for supplying direct current energy to the other end of the same line circuit, while these circuits have energized therefrom relays which are responsive only to one type of energy.

The system has been designed for use where a commercial source of alternating current is not available, and it is contemplated that the alternating current energy employed in the system will be generated locally by tuned reed alternators or similar devices. In order to reduce the number of these devices required the system has been arranged so that wherever possible the alternating current energy for several line circuits is supplied from one alternator.

In order to simplify the disclosure the tuned alternators have not been shown in the drawings, while the primary windings of the line circuit supply transformers are shown as connected to terminals BX and CX of a source of alternating current. This source may be a tuned alternator or it may be a commercial source of current, if such is available.

Each of the passing sidings has associated therewith line circuits I and II for energizing relays which control the signals at the ends of the siding.

In addition, each siding has extending from the eastern or right end thereof a line circuit III over which energy is supplied to a relay which controls the westbound approach signal to the siding.

Likewise, each siding has extending from the western or left end thereof a line circuit IV over which energy is supplied to a relay which controls the eastbound approach signal to the passing siding.

Each passing siding also has extending from the east or right end thereof a line circuit V which extends to the westbound distant signal for the passing siding and over which direct current energy is supplied to control the westbound distant signal for the passing siding and to also control lighting of the intermediate eastbound signal. In addition, alternating current is supplied over this line circuit to control the eastbound signals at the end of the passing siding.

In similar manner a line circuit VI extends from the left or west end of each passing siding to the first eastbound signal east of the adjacent passing siding to the west. Alternating current energy is supplied over this circuit to control certain of the eastbound signals, while direct current is also supplied over this circuit to control lighting of certain of the eastbound signals, and to also control the indications displayed by certain of the westbound signals.

A line circuit VII is also provided and controls the indication displayed by a westbound signal, while it also controls lighting of one of the eastbound signals. A line circuit VIII is also employed and controls the indication displayed by one of the eastbound signals.

Where both alternating and direct current is supplied over the same line circuit, a reactor RA is connected in series with the circuit to prevent flow of alternating current energy through the battery from which direct current energy is supplied to the circuit, while the direct current relays which are connected to the line circuit have windings of such high impedance as to substantially prevent flow of alternating current energy therein. In addition, these circuits have resistances RB connected in series therewith to limit the flow of direct current in the secondary

windings of the transformers from which alternating current energy is supplied to the circuits. Likewise, the circuits for connecting the relays responsive to alternating current across the line

5 circuits have resistances included in series therewith to limit the flow of direct current in the circuits of the primary windings of the transformers through which energy is supplied to these relays.

10 The equipment is shown in the condition which it assumes when the track stretch is vacant. At this time all of the track relays are picked up so that the various line circuits are complete and the relays energized therefrom are all picked up

15 and condition the various signals when lighted to display green or clear indications. At this time, however, as all of the relays are picked up, the circuits of the signal lamps are interrupted and all of the signals are dark.

20 *Operation of the equipment on movement of an eastbound train through the track stretch*

When a train moving from left to right advances a predetermined distance beyond the

25 passing siding west of the siding M, it releases a track relay, not shown, and thereby cuts off the supply of energy from a battery, not shown, to the line circuit VI associated with siding M, as will be clearly understood by reference to the corresponding equipment associated with passing siding N.

On interruption of the supply of direct current energy to the line circuit VI the relays 25WH and 23WH release and establish the circuits for

35 supplying energy to the lamps of the signals 26E and 24E.

At this time relay 26ED is picked up by current from transformer IVTT supplied over the line circuit IV and through the transformer and

40 rectifier associated with the relay. As relay 26ED is picked up, the circuit of the green lamp of signal 26E is established and this lamp is lighted to indicate that the track stretch in advance is vacant.

45 As the track stretch is assumed to be vacant, relay 24EH is picked up by direct current energy supplied over line circuit I, while relay 24ED is picked up by direct current energy supplied over line circuit II. As the relays 24EH and 24ED are picked up, the circuit of the green lamp of signal 24E is established, and this lamp is lighted to indicate that the track stretch in advance is vacant.

50 As the eastbound train proceeds through the track stretch, the westbound signals in advance of the train are conditioned to display appropriate signals when lighted so that two trains traveling in opposite directions will not collide head-on. This part of the operation of the system will be considered in detail below.

55 When the train under consideration advances into section 24T, track relay 24TR releases and interrupts line circuits I, IV and VI so that relay 26ED releases and conditions the signal 26E to display its yellow indication.

60 On release of track relay 24TR the supply of alternating current energy to the line circuit I is cut off and relay 21WH releases and establishes the circuit of the lamps of signal 22E. At this time relay 22EH is supplied with energy from transformer VTT over line circuit V so that its contact establishes the circuit of the green lamp of signal 22E and this lamp is lighted.

65 In addition, as a result of release of relay 70 21WH, the signal 21W is conditioned, when

lighted, to display its red or stop indication, while the supply of direct current energy from the battery IIIB to the line circuit III is cut off and relay 13WD releases and conditions the signal 13W, when lighted, to display its yellow or caution indication.

When the train advances from section 24T into section 23T, track relay 23TR releases and interrupts the supply of energy from battery IB over line circuit I to relay 24EH so that this relay releases while relay 21WH remains released. Release of relay 24EH conditions the signal 24E to display its red or stop indication.

When the train advances from section 23T into section 22T, relay 22TR releases and interrupts line circuit I to maintain relay 24EH released and thus cause signal 24E to continue to display its red or stop indication.

When the train vacates the section next in the west of section 24T, the track relay for this section picks up so that energy from a battery, not shown, feeds to the relay 25WH over line circuit VI and this relay picks up and interrupts the circuit of the signal 26E. Likewise, when the train vacates section 24T, relay 24TR picks up and energy is supplied over line circuit VI to relay 23WH and this relay picks up and interrupts the circuit of the signal 24E.

When the train advances into section 21T, relay 21TR releases and interrupts line circuits I, III and V. As the line circuit I is interrupted, energy is not supplied from the battery IB to relay 24EH so that this relay remains released and conditions the signal 24E when lighted to display its red or stop indication. As the line circuit III is interrupted by track relay 21TR, the relay 13WD will remain released after relay 21WH picks up, which occurs when the train vacates section 22T, and will continue to condition the signal 13W to display its yellow or caution indication as long as section 21T is occupied.

As a result of release of relay 21TR, the supply of direct current energy from the battery VB to the line circuit V is cut off and the relays 13AR and 12AR release and establish the circuits of the signals 13W and 12E, while the relay 11WH releases and conditions the signal 11W when lighted to display its red or stop indication. Furthermore as a result of the release of relay 11WH, circuit VII is interrupted and the supply of current from battery VIB ceases, whereupon relay 7WD releases and conditions signal 7W to display its yellow or caution indication when lighted.

The relays 13AR and 12AR are connected across resistors which are included in series with the line circuit and which are proportioned to produce sufficient voltage drop to operate the relays while not unduly restricting the flow of alternating current in the line circuit. Similarly the relay 11WH is connected across a resistor RB and the primary winding of the transformer VTT which together provide sufficient drop in the voltage of the direct current in the line circuit to operate the relay.

From the foregoing it will be seen that when the train advances beyond the passing siding M and enters section 21T, the signal 13W is conditioned to display its caution indication, while signal 11W is caused to display its stop indication when lighted.

When the train advances into section B13T, the relay B13TR releases and interrupts the line circuit V to maintain relays 12AR and 11WH

released and cause signal 11W when lighted to display its stop indication.

When the train vacates section 22T, relay 22TR picks up and energy from the transformer 5 ITT is supplied over the line circuit I to the relay 21WH and this relay picks up and interrupts the circuit of the signal 22E, while it also permits energy to be supplied from the battery IIIB to the line circuit III on picking up of relay 21TR which occurs when the train vacates section 21T.

When the train advances into section A13T, relay A13TR releases and cuts off the supply of energy from battery VIB to line circuit VI, while it also interrupts line circuit V to maintain relays 13AR, 12AR and 11WH released.

As a result of cutting off the supply of direct current to line circuit VI, the relay 11AR releases to establish the circuit to light signal 11W; relay 10AR releases to light signal 10E; relay 5WH releases to condition signal 5W when lighted to display its red or stop indication, and to establish the circuit of signal 6E; and relay 3WH releases to condition the signal 3W when lighted to display its stop indication, and to establish the circuit of signal 4E.

At this time relay 10ED is picked up by energy supplied over line circuit VIII and signal 10E displays its green or clear indication, while relay 12EH is picked up by energy from transformer 30 VTT supplied over line circuit VI so that signal 12E displays its green or clear indication and permits the train to advance beyond signal 12E into section 12T.

When the train does advance into section 12T, 35 relay 12TR releases and interrupts line circuit VI so as to cut off the supply of energy to the relay 12EH through the associated transformer and rectifier. The relay 12EH thereupon releases and conditions the signal 12E to display its red or stop indication.

When the train vacates section 21T, the track relay 21TR picks up and completes line circuit I and direct current from the battery IB feeds to the relay 24EH and this relay picks up and changes the aspect of signal 24E, when lighted, from red to yellow, while relay 24EH establishes line circuit IV so that energy is supplied to relay 26ED which picks up to condition the signal 26E when lighted to display its green or clear indication. In addition, relay 24EH, when picked up, permits energy to be supplied from line circuit II to relay 24ED after establishment of line circuit II by picking up of relay 22EH which does not take place until the train vacates section 11T. 55 Accordingly, the signal 24E, when lighted, will display its red indication until the train vacates section 21T, at which time the signal changes from red to yellow, while this indication will continue to be displayed until the train advances far enough to vacate section 11T.

When track relay 21TR picks up, it completes line circuit III and energy is supplied to the relay 13WD so that this relay picks up to condition the signal 13WD to display its green or clear indication.

When the train advances into section 11T, the relay 11TR releases and interrupts line circuits V, VI and VII. Line circuits V, VI and VII were already interrupted so release of relay 11TR does not change the condition of these circuits.

When the train advances into section 10T, relay 10TR releases and additionally interrupts line circuits VI and VII and there is no change in the signals at this time.

When the train advances into section 8T, the

relay 8TR releases and additionally interrupts the line circuits VI and VII, while it also interrupts the line circuit VIII so that relay 10ED releases and conditions the signal 10E to display its yellow or caution indication.

When the train vacates section 12T, the relay 12TR picks up and energy is supplied from the battery VB to energize the relays 13AR, 12AR and 11WH in series and these relays pick up so that signals 13W and 12E are extinguished, while signal 11W is conditioned to display its green instead of its red indication.

When the train advances far enough to vacate section 11T, the track relay 11TR picks up and the line circuit V is again complete and energy is supplied over this line circuit from the transformer VTT to the relay 22EH and this relay picks up to condition the signal 22E when lighted to display its green or clear indication. In addition, picking up of relay 22EH completes line circuit II so that energy from the battery 11B picks up the relay 24ED to thereby condition the signal 24E when lighted to display its green or clear indication.

When the train advances into section 6T, relay 6TR releases and cuts off the supply of energy from the transformer VITT over the line circuit VI to the relay 8EH and this relay releases and conditions the signal 8E to display its red or stop indication, while it also establishes the circuit of the signal 7W.

When the train is present in section 6T, the relay 5WH is released as the line circuit VI is interrupted by contacts of relay 6TR, and as relay 5WH is released, the circuit of the signal 6E is established. At this time, as the track stretch is assumed to be vacant except for the train in section 6T, the relay 6ED is picked up by energy supplied over line circuit IV and the signal 6E is conditioned to display its green or clear indication. In addition, as the line circuit VI is interrupted, the relay 3WH is released and conditions the signal 3W, when lighted, to display its red or stop indication to thereby prevent a westbound train leaving the passing siding N while the eastbound train is approaching the siding.

As the train advances from section 6T into section 4T and on past the passing siding N, the signals associated with the passing siding N operate in the manner explained in connection with passing siding M and a detailed description of their operation is not necessary.

Operation of the system on movement of a westbound train through the track stretch

For purposes of illustration it will be assumed that the track stretch is vacant and that a westbound train passes through the track stretch.

When the westbound train is present in section 1T, the track relay 1TR is released and interrupts the line circuits I, III and V. As line circuit I is interrupted by track relay 1TR, direct current from the battery 1B is not supplied over the circuit to relay 4EH, but energy is supplied from the transformer ITT to relay 1WH.

As line circuit V is interrupted, relay 2EH is released and establishes the circuit of the signal 1W. At this time relay 1WH is picked up, as pointed out above, while relay 1WD is picked up by energy supplied from the transformer ITT over the line circuit II. As relays 1WD and 1WH are picked up, signal 1W is conditioned to display its green or clear indication.

At this time relay 3WH is picked up by energy supplied from the battery VIB over the line circuit

VI, while the relay 4EH is released, as explained above, and the signal 3W is conditioned to display its green or clear indication.

In addition, as relay 4EH is released line circuit 5 IV is interrupted and relay 6ED is released and establishes the circuit of the signal 5W so this signal displays its green or clear indication, while the signal 4E when lighted will display its red or stop indication.

10 When the train advances into section 2T, the track relay 2TR releases and cuts off the supply of energy over line circuit I to the relay 1WH with the result that signal 1W displays its stop indication.

15 When the train advances into section 3T, the track relay 3TR releases and interrupts line circuit I to maintain relays 4EH and 1WH released and thereby maintain signal 1W at stop and to also maintain the circuit for lighting the signal 3W.

20 When the train vacates section I, relay 1TR picks up and completes line circuit V so that energy is supplied to relay 2EH and this relay picks up to interrupt the circuit of the signal 1W.

When the train advances into section 4T, track relay 4TR releases and interrupts line circuits I, IV and VI. Interruption of line circuit I maintains relay 1WH released so that the signal 1W when lighted will display its stop indication, while 30 interruption of line circuit IV maintains relay 6ED released to maintain the circuit of the signal 5W.

35 Interruption of the line circuit VI by the track relay 4TR cuts off the supply of alternating current from the transformer VITT to the line circuit VI and relay 6EH releases and establishes the circuit of signal 1W. At this time relay 7WD is picked up by energy supplied over the line circuit VII and the signal 1W is conditioned to display its green or clear indication.

40 In addition, on release of relay 8EH line circuit VIII is interrupted and relay 10ED releases and conditions the signal 10E when lighted to display its yellow or caution indication.

45 On release of relay 4TR and interruption of the supply of alternating current to the line circuit VI relay 12EH releases and conditions signal 12E when lighted to display its red or stop indication.

50 Interruption of the line circuit VI by the track relay 4TR cuts off the supply of direct current energy over the line circuit VI to the relay 3WH and this relay releases to condition the signal 3W to display its stop indication. Release of relay 4TR does not affect the supply of energy from the battery VIB to the relays 11AR, 10AR and 5WH over the line circuit VI and these relays are energized in series. Accordingly, the relay 5WH remains picked up and conditions the signal 5W to display its green or clear indication.

60 When the train advances into section 6T, relay 6TR releases and interrupts the line circuit VI so as to interrupt the series connection of the relays 11AR, 10AR and 5WH and these relays thereupon release. Release of relay 11AR establishes the

65 circuit of the signal 11W, while release of relay 10AR establishes the circuit of the signal 10E, and release of relay 5WH conditions signal 5W to display its red or stop indication.

70 When the train vacates section 2T, track relay 2TR picks up, while when the train vacates section 3T, the track relay 3TR picks up and energy is supplied from battery 1B over line circuit I to relay 4EH. As a result, relay 4EH picks up and interrupts the circuit of signal 3W.

When the train vacates section 4T, the track relay 4TR picks up and completes line circuits I and IV. As a result, energy from the transformer ITT is supplied to the relay 1WH over the line circuit I and this relay picks up to interrupt the circuit of the signal 2E and to condition the signal 1W when lighted to display its green or its yellow indication. As the line circuit IV is complete, energy from the transformer IVTT is supplied to the relay 6ED and this relay picks up and interrupts the circuit of the signal 5W.

When the train advances into section 8T, relay 8TR releases and interrupts line circuits VI, VII and VIII. As a result of interruption of line circuit VII, relay 7WD releases and causes the signal 1W to display its caution indication, while interruption of line circuit VIII maintains relay 10ED released after the train vacates section 6T and relay 8EH picks up.

When the train advances into section 10T, relay 10TR releases and interrupts line circuits VI and VII so that relay 7WD remains released and relays 11AR, 16AR and 5WH also remain released.

When the train vacates section 6T, relay 6TR picks up so that energy from the transformer VITT feeds to the relay 8EH over the line circuit VI and relay 8EH picks up and interrupts the circuit of the signal 7W.

When the train vacates section 8T, the relay 8TR picks up and completes line circuit VIII so that relay 10ED picks up and conditions signal 16E to display its green or clear indication.

When the train advances into section 11T, track relay 11TR releases and interrupts line circuits V, VI and VII. Interruption of line circuit V cuts off the supply of energy from the transformer VTT to relay 22EH and this relay thereupon releases and conditions signal 22E when lighted to display its red or stop indication.

At this time relay 11AR is released as line circuit VI is interrupted, while relay 11WH is picked up by energy supplied from battery VB over line circuit V. Accordingly, the signal 11W displays its green or clear indication.

When the train advances into section 12T, track relay 12TR releases and interrupts line circuits V and VI. Interruption of line circuit V by the relay 12TR interrupts the circuit for energizing 13AR, 12AR and 11WH in series from the battery VB and these relays thereupon release. Release of relay 11WH causes signal 11W to display its red or stop indication, and interrupts circuits VII to continue the deenergization of relay 7WD, while release of relays 12AR and 13AR establishes the circuits of the signals 12E and 13W. At this time relay 12EH is released as line circuit VI is interrupted and accordingly signal 12E displays its stop indication. In addition, at this time relay 13WD is picked up by energy supplied over line circuit III so that signal 13W displays its green or clear indication.

When the train vacates sections 10T and 11T, the track relays 10TR and 11TR pick up. However, relay 11WH is released and maintains circuit VII deenergized so that energy is not supplied to relay 7WD and signal 1W when lighted displays its yellow or caution indication.

When the train advances into section A13T, the track relay A13TR releases and additionally interrupts the line circuits V and VI, while when the train advances into section B13T, the track relay B13TR releases and additionally interrupts line circuit V.

When the train advances into section 21T, relay 21TR releases and interrupts line circuits I, III and V. On this interruption of the line circuit I the supply of energy from the battery 1B to the relay 24EH is cut off, but the supply of energy from the transformer ITT to the relay 21WH is maintained. At this time relay 21WD is picked up by energy supplied from transformer ITT over line circuit II, while relay 22EH is released as line circuit V is interrupted, and accordingly signal 21W is lighted and displays its green or clear indication.

As relay 24EH is released, the circuit of signal 23W is established, while this signal displays its green indication as relay 24WH is picked up by energy supplied over line circuit VI.

As line circuit III is interrupted, relay 13WD is released, and as line circuit V is interrupted, relay 13AR is released so that signal 13W is lighted and displays its yellow or caution indication.

When the train vacates section 12T, relay 12TR picks up and energy from the transformer VITT is supplied over the line circuit VI to the relay 12EH and this relay picks up to condition the signal 12E to display its green or clear indication.

Picking up of track relay 12TR does not permit the supply of energy from the battery VIB to the line circuit VI and accordingly relays 3WH and 5WH remain released. As relay 3WH is released, the signal 3W when lighted will display its red or stop indication to warn a second or following westbound train of the presence of the first train in the track stretch. Likewise, as relay 5WH is released, the signal 5W when lighted will display its red or stop indication.

When the train vacates section A13T, track relay A13TR picks up and completes line circuit VI so that energy from the battery VIB is supplied over the line circuit VI to the relays 11AR, 10AR, 5WH and 3WH. As relays 5WH and 3WH are picked up, the signals 5W and 3W when lighted display their green or clear indications. As relays 11AR and 10AR are picked up, the signals 11W and 10E are dark.

When the train vacates section B13T, the relay B13TR picks up, but line circuit V continues to be interrupted by track relay 21TR and relay 11WH remains released and conditions the signal 11W when lighted to display its red or stop indication as long as section 21T is occupied.

Line circuit VII continues to be interrupted by relay 11WH and relay 7WD remains released and conditions signal 1W when lighted to display its yellow or caution indication as long as circuit V is interrupted.

As the train proceeds through the track stretch past the passing siding M, the signals associated with this passing siding operate as described in connection with passing siding N and a detailed explanation of their operation is not necessary.

Operation of system in response to movement of trains through the track stretch in opposite directions

The system provided by this invention is arranged so that when trains moving in opposite directions are present in the track stretch intermediate two passing sidings, the signals in advance of each train and controlling movement of traffic in the opposite direction are governed in such manner that the trains are given adequate warning of the approach of each other so that they can stop before colliding head-on.

When an eastbound train advances beyond passing siding M into section 21T, relay 21TR

interrupts line circuit V so that energy is not supplied over this circuit to the relays 13AR, 12AR and 11WH. As relay 11WH is released, the signal 11W when lighted displays its stop indication to prevent a westbound train from proceeding beyond this point. Furthermore, with the release of relay 11WH line circuit VII is interrupted to cause the release of relay IWD. As relay IWD is released, the signal 1W when lighted displays its yellow or caution indication.

The lighting of signal 11W is controlled by relay 11AR which is energized from line circuit VI and becomes released when a westbound train enters section 6T, and the lighting of signal 1W is controlled by relay 8EH which is energized by transformer VITF over circuit VI and becomes released when a westbound train enters section 4T. Accordingly, when an eastbound train is present in section 21T, a westbound train is first warned by signal 1W and is prevented from proceeding beyond signal 11W. The westbound train having approached signal 11W with caution will be able to stop before passing that signal, and therefore will not collide with the eastbound train.

As soon as a westbound train advances beyond passing siding N and enters section 4T, line circuit VI is interrupted so that energy from the transformer VITF is not supplied to the relay 12EH and this relay releases and causes the signal 12E to display its stop indication. Accordingly, the eastbound train which was assumed to be present in section 21T will not advance beyond signal 12E. Since the westbound train is prevented from advancing beyond signal 11W, the two trains are separated by section 12T and are prevented from colliding.

When an eastbound train advances into section A13T, the track relay A13TR interrupts the line circuit VI so that energy is not supplied from the battery VIB over the line circuit VI to the relays 5WH and 3WH and these relays are released to condition the signals 5W and 3W to display stop indications. The release of relay 3WH interrupts line circuit II which releases relay IWD to condition that signal to display its yellow or caution indication when lighted. As the signal 3W displays a stop indication and signal 1W displays a caution indication, a westbound train is prevented from proceeding beyond the passing siding N and the eastbound train can continue until it reaches passing siding N.

If a westbound train is present in section 3T waiting for the eastbound train, relay 4EH will be released and will interrupt line circuit IV so that relay 6ED is released and signal 6E displays a caution indication to cause the eastbound train to approach the passing siding slowly.

In similar manner the equipment operates to prevent a head-on collision between trains if a westbound train advances beyond a passing siding before an eastbound train does.

If, for example, a westbound train enters section 4T, line circuit VI is interrupted so that energy from the transformer VITF is not supplied to the relays 8EH and 12EH and these relays release and cause signals 8E and 12E when lighted to display red or stop indications and thereby prevent movement of eastbound trains beyond these points.

If an eastbound train now enters section 21T, line circuit V is interrupted and relay 11WH releases and signal 11W is conditioned to display its stop indication. Relay 11WH when released interrupts line circuit VII and releases relay IWD

and signal 1W is conditioned to display its caution indication. Accordingly, a westbound train approaches signal 11W with caution and would not advance beyond signal 11W, while an eastbound train would not advance beyond signal 12E and the two trains would be separated by block 12T.

If before an eastbound train enters section 23T the westbound train advances into section 11T, the track relay 11TR will interrupt the line circuit V and prevent the supply of energy from the transformer VTT to the relay 22EH. Relay 22EH when released interrupts circuit II so that direct current energy ceases to flow from battery 11B and relay 24ED releases. As relay 22EH is released, signal 22E is conditioned to display its stop indication and since relay 24ED is released, signal 24 is conditioned to display its caution indication. Accordingly, an eastbound train will approach signal 22E with caution and will not proceed beyond the passing siding M.

From the foregoing it will be seen that the system provided by this invention provides improved means for controlling the signals which govern movement of traffic in both directions over a track stretch, and that the system functions to provide protection both for trains moving in the same direction and for trains moving in opposite directions. In addition, it will be seen that several of the line circuits are arranged so that alternating current is supplied to one end of the line conductors, and direct current to the other end of the line conductors so that these line circuits serve two functions, thereby reducing the number of line circuits required.

The system provided by this invention is adapted for use where semaphore signals are employed and Fig. 2 is a diagram showing this modification of the invention.

40 Construction and operation of modification shown in Fig. 2

Fig. 2 is a fragmentary view similar to Fig. 1 and showing the portion of the track stretch between the passing siding M and the signal 11W. This track stretch is shown equipped with semaphore signals which may be of any well-known construction. One form of signal which may be employed is shown in United States Patent No. 1,307,741 issued June 24, 1919, to Lloyd V. Lewis. Each of these signals has a semaphore arm which is movable from a horizontal or stop position to a position in which it provides a proceed indication. This may be a 45° position in which it indicates caution, or a 90° position in which it indicates clear, while some or all of the signals may be arranged to provide both indications.

Each of the signals is provided with an electric motor for moving the semaphore arm from its stop to its proceed positions, while each of the signals also is provided with a holding coil K which when energized establishes a driving connection between the motor and the semaphore arm so that the motor will move the arm. In addition, the holding coils when energized serve to hold the semaphore arms in the positions to which they have been moved.

The signals each also have a lamp which is mounted so that light from the lamp is projected through roundels carried by the semaphore arm. These roundels have different colored lenses mounted therein and are positioned so that when the semaphore arm is in its horizontal or stop position, a red lens is located in

front of the lamp; when the semaphore arms is in its 45° position, a yellow lens is located in front of the lamp; while when the semaphore arm is in its 90° or vertical position, a green lens is located in front of the lamp. The circuits of the lamps of the signals are approach controlled so that the lamps are normally dark and become lighted on the approach of a train.

The signals employed in the modification shown in Fig. 2 are provided with holding coils having two windings, one of which is energized in series with the motor for moving the semaphore arm, while the other winding is energized from the line circuit over which energy is supplied to the relay which controls the signal.

The equipment is shown in the condition which it assumes when the track stretch is vacant. At this time the track relays are picked up and the line circuit V is complete so that energy from the battery VB is supplied over the line circuit to energize the relays 13AR and 12AR and the winding 31 of the holding coil K of signal 11W in series.

As the relays 13AR and 12AR are picked up, the circuits of the signal lamps controlled thereby are interrupted, while as winding 31 of holding coil K of signal 11W is energized, the semaphore arm of this signal is held in its 90° or vertical position to provide the clear indication. As the signal arm is in its 90° position, the signal controlled contacts are open and interrupt the supply of energy from the line circuit to the winding of relay 11WH. The signal controlled contacts are arranged so as to be closed in all positions of the semaphore arm except its vertical or 90° position.

As the relay 11WH is released, its contacts interrupt the circuit for supplying energy from a battery to the motor J which moves the semaphore arm.

In like manner, energy from the transformer VTT is supplied over the line circuit and through the transformer and rectifier associated with signal 22E to the winding 31 of the holding coil K of this signal. As this holding coil winding is energized, the semaphore arm of this signal is held in its 90° or vertical position to provide the clear indication. As the signal arm is in its 90° position, the signal controlled contacts are open and energy from the line circuit is not supplied to the relay 22EH so that this relay is released and interrupts the circuit of the switch motor J.

If an eastbound train enters section 21T, track relay 21TR releases and interrupts line circuit V so that the supply of energy from the transformer VTT to the winding 31 of holding coil K is cut off and the holding coil releases the semaphore arm. Accordingly, the semaphore arm drops to its horizontal or stop position, thereby closing the signal controlled contacts. However, at this time no energy is supplied to the relay 22EH as the track relay 21TR is released and relay 22EH remains released and interrupts the circuit of the signal motor J.

Release of track relay 21TR also cuts off the supply of energy from the battery VB to the line circuit V and thus to the winding 31 of the holding coil K of signal 11WH and this coil releases the semaphore arm of the signal so that this arm moves to its horizontal position to provide the stop indication.

When the train advances far enough to vacate section 12T, the relay 12TR picks up and energy from the battery VB is supplied to the relay 11WH and to winding 31 of holding coil K in multiple.

The circuit for supplying energy to the relay 11WH is complete as the semaphore arm of the signal 11W is in its horizontal or stop position and the signal controlled contacts are closed.

- 5 On the supply of energy to the winding 31 of the holding coil K the magnet operates in the manner well-known in the art to establish driving connection between the motor and the semaphore arm so that the motor will move the semaphore arm to the vertical position. When energy is supplied to the relay 11WH, its contacts pick up and establish the circuit to supply energy from a battery to the motor J and winding 32 of the holding coil K in series. On the supply of energy 10 to the motor J it operates in the customary manner to move the semaphore arm from its horizontal to its vertical or clear position.
- 15 At this time the windings 31 and 32 of holding coil K are both energized and these windings are arranged so that they assist each other to maintain the driving connection between the motor and the semaphore arm. When the arm is being moved by the motor, there is a possibility that the driving connection between the motor and the arm may be disrupted unless it is firmly established. The arrangement provided by this invention is such that both windings of the holding coil are energized while the arm is being driven by the motor so that the maximum force is exerted 20 to maintain the driving connection between the motor and the signal arm to thereby insure that this connection will be maintained.

When the signal arm reaches its vertical or 90° position, the signal controlled contacts open 35 and interrupt the supply of energy to the relay 11WH so that the contacts of this relay release and interrupt the supply of energy to the motor J and to the winding 32 of the holding coil K. The winding 31 of the holding coil K continues 40 to be energized from the line circuit V and maintains the semaphore arm in its vertical or clear position.

When the train advances far enough to vacate section 11T, the track relay 11TR picks up and energy from the transformer VTT is supplied over the line circuit V through the transformer and rectifier associated with the line circuit to the relay 22EH and to the winding 31 of the holding coil K associated with signal 22E.

45 50 On the supply of energy to the holding coil K it establishes driving connection between the motor J and the signal arm, while the relay 22EH when picked up establishes the circuit to supply energy to the motor J and to the winding 32 of the holding coil K so that the motor moves the semaphore arm to its clear position.

When the semaphore arm reaches its 90° or clear position, the signal controlled contacts open and interrupt the supply of energy to the relay 22EH, and this relay releases and cuts off the supply of energy to the motor J and the winding 32 of the holding coil K. Thereafter the signal arm is held in its vertical position by the winding 31 of the holding coil which continues to be 55 energized over the line circuit V.

The signals operate in substantially the same manner on movement of a westbound train through the track stretch.

In addition, it is contemplated that the system shown in Fig. 2 will include other line circuits and associated apparatus as shown in Fig. 1 to control signals 21W, 13W and 12E, and to also control lighting of the lamps, not shown, associated with signals 22E and 11TR. In order to

simplify the disclosure these have been omitted from Fig. 2.

Construction of modification shown in Fig. 3 of the drawings

The modification shown in Fig. 3 of the drawings is similar to that shown in Fig. 1, but provides means to provide a larger number of signal indications than the system shown in Fig. 1, while it requires fewer line wires than the system shown in Fig. 1.

The modification shown in Fig. 3 of the drawings, like that shown in Fig. 1, employs direct current in a line circuit to control the signals for one direction of traffic, and employs alternating current in the same line circuit to control the signals for the other direction of traffic. The system shown in Fig. 3 differs from that shown in Fig. 1 in that it employs the two polarities of direct current to provide two proceed indications, while it employs coded and steady alternating current energy to also provide two proceed indications.

Referring to Fig. 3 of the drawings, there is shown therein a stretch of single track railroad having track rails 1 and 2 over which traffic moves in both directions. The rails of the track are divided by insulated joints into the customary track sections, while passing sidings are provided at appropriate intervals to permit traffic to be diverted from the main track under the customary control of switches, not shown. Two such passing sidings are shown and are designated P and Q.

As in the system shown in Fig. 1, it will be assumed that the right-hand end of the track stretch is east and that the left-hand end is west. Likewise, in the system shown in Fig. 3 the signals governing westbound traffic are identified by odd numbers, while the signals governing eastbound traffic are identified by even numbers. The signals starting at the east end of passing siding Q are numbered in a series starting with 1W, while the signals starting at the east end of passing siding P are numbered in a series starting with 2W. The reference characters for the westbound signals include the suffix W, while the reference characters for the eastbound signals include the suffix E. The track sections are numbered in a series corresponding to that of the signals.

The signals are shown as being of the color light type, while each of the signals has associated therewith a local source of direct current, the terminals of which are designated (+) and (-). While color light signals are shown, the invention is not limited to the use of signals of this type and any desired form of signals may be employed.

Each of the track sections is provided with a track circuit including a track battery connected across the section rails at one end of the section, and a track relay, designated TR with a suitable prefix, connected across the section rails at the other end of the section.

This system, like that shown in Fig. 1, employs line circuits for controlling the signals, while these line circuits are controlled by contacts of the track relays.

In the system shown there is a line circuit X which is substantially coextensive with the passing siding Q, while a line circuit XI extends westward from the passing siding Q and overlaps a line circuit XII which extends eastward from the adjacent passing siding P to the west. Simi-

larly there is a line circuit XX which is substantially coextensive with the passing siding P, while a line circuit XXI extends westward from the passing siding P.

- 5 Each of the line circuits has a battery at one end thereof, and a transformer at the other end thereof. In addition, each circuit has a reactor RA included therein to limit the flow of alternating current in the battery and a resistance RB to substantially limit the flow of direct current in the transformer secondary winding. Each of the line circuits has a direct current relay energized by direct current supplied over the line circuit and also has a direct current relay energized from the line circuit through a transformer and a rectifier so that the relay is energized only when alternating current energy is supplied over the line circuit.

The equipment is shown in the condition which 20 it assumes when the track stretch is vacant. At this time the track relays are picked up and the various line circuits are all complete.

As the line circuit X is complete, energy from 25 the battery XB is supplied over the line circuit to the relay 1WR so that the neutral contacts of this relay are picked up. As the neutral contacts of relay 3WR are picked up, the polarity of the energy supplied from the battery XB to the relay 1WR is such that the polar contacts of the relay 30 1WR occupy their left-hand or normal positions as shown. Accordingly, the green or clear lamp G of signal 1W is lighted by energy supplied over the circuit which is traced from one terminal of a local source of current through front contact 35 103 and normal polar contact 101 of relay 1WR and lamp G to the other terminal.

In addition, at this time a circuit is established 40 to supply coded alternating current energy to line circuit IX which extends to the east of passing siding Q. The coded energy is provided by a code transmitter CT which, like the other code transmitters employed in this system, has a contact 180 which is continuously operated by a motor or other means at a rate effective to provide 180 energy impulses a minute separated by periods of equal length during which no energy is supplied. While the system is described as employing energy of 180 code frequency, it should be understood that any other code frequency 45 may be employed.

The circuit for supplying energy to the line 50 circuit IX is traced from terminal BX of a source of alternating current through contact 180 of code transmitter CT, normal polar contact 102 and neutral front contact 103 of relay 1WR, and the primary winding of transformer IXTT to terminal CX. The secondary winding of the transformer IXTT is included in series with the line circuit IX.

60 At this time relay 2ER is energized by direct current supplied over line circuit IX and its contacts establish a circuit to light the green or clear lamp of signal 2E. This circuit is traced from one terminal of a source of current through front contact 105, normal polar contact 106 of relay 2ER, and lamp G of signal 2E to the other terminal.

In addition, relay 2ER establishes a circuit to 65 supply coded alternating current energy to line circuit X. This circuit is traced from terminal BX through front contact 108 of relay 2ER, contact 180 of code transmitter CT and primary winding of transformer XTT to terminal CX. The secondary winding of the transformer is included in series with the line circuit X, and as

the contacts of track relays 1TR, 2TR and 3TR are picked up, coded energy is supplied over the line circuit X to relay 4ER through the associated transformer and rectifier.

As a result of code following operation of the relay 4ER, energy is supplied to relay 4H during the picked-up periods of the contacts of relay 4ER. The relay 4H is of the type which is slow to release so its contacts remain picked up between the supply of impulses of energy thereto. As contact 110 of relay 4H is picked up, the circuit of the primary winding of decoding transformer 4DT is established so that as long as relay 4ER follows coded energy current is supplied through the decoding transformer 4DT to the relay 4J and the contacts of this relay are picked up. As relays 4H and 4J are both picked up, a circuit is established to light the green or clear lamp of signal 4E. This circuit includes front contact 111 of relay 4H and front contact 112 of relay 4J.

In addition, at this time coded alternating current energy is supplied to transformer XITT over a circuit which is traced from terminal BX through contact 180 of a code transmitter CT, front contact 114 of relay 4J, front contact 115 of relay 4H and primary winding of transformer XITT to terminal CX.

In like manner, the relays 5WR, 6ER and 24ER respond to coded alternating current supplied over the line circuits XII, XI and XX so that the signals 5W, 6E and 24E are conditioned to display green or clear indications, while relay 24ER causes coded alternating current to be supplied to line circuit XXI. Similarly, the relays 3WR, 21WR, 22ER and 23WR are energized by direct current energy supplied over the line circuits XI, XII, XX and XXI and condition the signals 3W, 21W, 22E and 23W to display green or clear indications, while relay 22ER establishes the circuit to supply coded alternating current to the line circuit XII.

Operation of equipment on movement of an east-bound train through the track stretch

When an eastbound train enters section 24T, the track relay 24TR releases and cuts off the supply of direct current to line circuit XX, while it also interrupts line circuit XXI so that relay 23WR releases. Deenergization of relay 23WR causes signal 23W to display its red or stop indication to prevent a westbound train from advancing beyond the passing siding P. The circuit of the red lamp of signal 23W includes back contact 120 of relay 23WR.

Release of track relay 24TR does not affect the supply of energy from transformer XITT over line circuit XX to relay 24ER, but it cuts off the supply of energy from battery XXB to relay 21WR. Release of relay 21WR interrupts the circuit of the green lamp G and establishes the circuit of the red lamp R of signal 21W. The circuit of the lamp R of signal 21W includes back contact 121 of relay 21WR.

Deenergization of relay 21WR also interrupts the circuit for supplying coded energy to the line circuit XII and establishes a circuit to supply steady uncoded alternating current to this circuit. This circuit includes back contact 122 of relay 21WR.

As a result of the change in the alternating current energy supplied to line circuit XII from coded to steady, the relay 5WR ceases to follow code so that relay 5J releases, while the contacts of relay 5WR remain picked up so that energy

is supplied to relay 5H and this relay remains energized. On release of relay 5J while relay 5H is picked up, the green lamp G of signal 5W is extinguished and the yellow lamp Y is lighted. The circuit of the lamp Y includes front contact 124 of relay 5H and back contact 125 of relay 5J.

It will be seen, therefore, that when a train is present in section 24T, the signals 23W and 21W are both conditioned to display red or stop indications, while the signal 5W is conditioned to display its yellow or caution indication. Accordingly, a westbound train will receive a restrictive indication before reaching the passing siding and will receive a stop indication at the east end of the siding P. This insures that the westbound train will have ample warning of the approach of an eastbound train.

When the eastbound train advances into section 23T, relay 23TR releases and additionally cuts off the supply of energy from the battery XXB to line circuit XX, while it also cuts off the supply of energy from the transformer XITT to the relay 24ER so that this relay ceases to respond to coded energy. On deenergization of relay 24ER relays 24H and 24J release and interrupt the circuit of the green lamp G of signal 24E and establish the circuit of the red lamp R of this signal. The circuit of the red lamp includes back contact 126 of relay 24H. In addition, as a result of release of relay 24H, contact 127 interrupts the circuit of the primary winding of decoding transformer 24DT to thereby prevent consumption of energy by this transformer at this time.

As a result of the release of the relays 24H and 24J, the circuit for supplying coded energy to the transformer XITT is interrupted and a circuit including back contact 128 of relay 24H is established to supply steady uncoded energy to this transformer. On this change in the energy supplied to line circuit XIT the eastbound signal next in the rear of signal 24E will be conditioned to display a yellow or caution indication when the train vacates section 24T.

When the train advances into section 22T, track relay 22TR releases and additionally interrupts line circuit XX, while there is no other change in the equipment at this time.

When the train vacates section 24T, track relay 24TR picks up and permits energy to be supplied over line circuit XXI to relay 23WR and this relay establishes the circuit of the green lamp G of signal 23W. This circuit includes front contact 120, normal polar contact 130 and lamp G of signal 23W.

When the train vacates section 23T, track relay 23TR picks up, but there is no other change in the equipment at this time.

When the train enters section 21T, 21TR releases and interrupts the line circuits XX and XII. In interruption of line circuit XII relays 22ER and 5WR release. Release of relay 22ER cuts off the supply of coded alternating current energy to line circuit XX and establishes a circuit to supply steady energy to this circuit, while it also conditions signal 22E to display its red or stop indication. The circuit of the red lamp R of signal 22E includes back contact 131 of relay 22ER, while the circuit for supplying steady alternating current energy to the line circuit XX includes back contact 132 of relay 22ER. At this time as section 21T is occupied and track relay 21TR is released, energy is not supplied from the transformer XITT to the line circuit XX so relay 24ER remains released and the sig-

70
75

nal 24E continues to display its stop indication.

As a result of interruption of the supply of energy to relay 5WR, the relay 5H releases and interrupts the circuit of the yellow lamp Y of signal 5W and establish the circuit of the red lamp R of this signal. The circuit of the red lamp includes back contact 124 of relay 5H. On release of relay 5H its contact 123 interrupts the circuit of the primary winding of transformer 5DT.

In addition, on release of relay 5H contacts 134 and 135 of this relay reverse the polarity of the energy supplied from the battery XIB over the line circuit XI to relay 3WR so that the polar contact 137 of relay 3WR is shifted from its normal to its reverse position to thereby interrupt the circuit of the green lamp G of signal 3W and establish the circuit of the yellow lamp Y. The circuit of the yellow lamp Y includes front neutral contact 138 and reverse polar contact 137 of relay 3WR.

It will be seen, therefore, that as soon as an eastbound train advances beyond the passing siding P and enters section 21T, line circuit XII is interrupted so that relay 5WR is deenergized and conditions the signal 5W to display its red or stop indication, while the polarity of the energy supplied to line circuit XI is changed so that relay 3WR conditions signal 3W to display its yellow or caution indication. Accordingly, a westbound train will receive a caution indication from signal 3W and would be prevented from proceeding beyond signal 5W so that it will not collide with the eastbound train.

When the eastbound train advances into section 1T, the track relay 7TR releases and interrupts the line circuits XII and XI. Interruption of line circuit XII maintains relay 5WR deenergized to thereby cause signal 5W to continue to display its stop indication, while interruption of line XI cuts off the supply of energy to relay 3WR so that the neutral contact 138 of this relay releases and interrupts the circuit of the yellow lamp Y of signal 3WR and establishes the circuit of the red lamp R of this signal.

In addition, on release of the neutral contacts of relay 3WR contacts 140 and 141 change the polarity of the energy supplied from battery XB to line circuit X so that the polar contacts of relay 1WR are shifted from their normal to their reverse positions. On this movement of contact 101 of relay 1WR the green lamp G of signal 1W is extinguished and the yellow lamp Y of this signal is lighted. On movement of contact 102 to its reverse position the supply of coded energy to the line circuit IX is cut off and steady alternating current energy is supplied to this circuit so that the westbound signal next in the east of signal 1W is caused to display a yellow instead of a green induction.

As a result of signal 1W and the signal next to the east displaying caution indications, a westbound train approaching siding Q would receive ample warning of a meet with the eastbound train to enable the westbound train to stop at signal 1W and enter siding Q.

When the train vacates section 22T, relay 22TR picks up so that energy from the battery XXB is supplied to the relay 21WR and the neutral contacts of this relay pick up, while the polar contacts of the relay occupy their normal position. As a result of this energization of the relay 21WR, contact 121 is picked up and contact 142 occupies its normal position so that

the circuit of the green lamp G of signal 21W is complete.

In addition, as contact 122 of relay 21WR is picked up and contact 143 occupies its normal position, the circuit for supplying energy of 180 code frequency to the transformer XITT is complete. However, at this time the line circuit XII is interrupted by track relays 21TR and 7TR so that energy is not supplied over the line circuit to relay 5WR.

When the train advances into section 6T, track relay 6TR releases and additionally interrupts line circuit XII, while it interrupts line circuit XI in such manner as to cut off the supply of energy over this line circuit from the transformer XITT to the relay 6ER. Relay 6ER, therefore, ceases to follow code and relays 6H and 6J release and condition signal 6E to display its red or stop indication. The circuit of the red lamp of signal 6E includes back contact 145 of relay 6H, while contact 147 of relay 6H cuts off the supply of energy to the decoding transformer 6DT. In addition, on release of relay 6H contacts 148 and 149 of this relay establish connections to supply energy of reverse polarity instead of normal polarity from the battery XIIB to the line circuit XII.

When the rear of the train vacates section 21T, track relay 21TR picks up and completes line circuit XX so that energy from the transformer XXTT is supplied to the relay 24ER. At this time neutral contact 132 of relay 22ER is released as line circuit XII is interrupted. Accordingly, steady energy is supplied to the transformer XXTT and is supplied therefrom to relay 24ER so that the contacts of this relay pick up and establish the circuit of relay 24H. Energy is not supplied through the decoding transformer 24DT to relay 24J so that a circuit is established including front contact 126 of relay 24H and back contact 150 of relay 24J to light the yellow lamp Y of signal 24E.

At this time steady energy continues to be supplied to the transformer XXTT over a circuit which includes back contact 151 of relay 24J and front contact 128 of relay 24H, so that the eastbound signal next in the west of signal 24E is conditioned to display a yellow or caution indication.

When the train advances into section 5T, the track relay 5TR releases and additionally interrupts line circuits XII and XI, but there is no change in the condition of the signals at this time.

When the rear of the train vacates section 7T, track relay 7TR picks up, but there is no change in the signals as relay 6TR interrupts line circuits XII and XI.

When the train advances into section 4T, the track relay 4TR releases and interrupts line circuit X so that energy from the battery XB is no longer supplied to the relay 1WR. Accordingly, the neutral contacts of relay 1WR release and contact 103 establishes the circuit of the red or stop lamp R of signal 1W, while contact 103 establishes the circuit to supply steady energy to the transformer IXTT with the result that the next westbound signal east of signal 1W remains conditioned to display its caution indication.

At this time relay 4ER continues to receive coded energy over the line circuit X from the transformer XTT so that signal 4E continues to display its green or clear indication.

When the rear of the train vacates section 6T,

track relay 6TR picks up so that coded energy from the transformer XIITT is supplied over the line circuit XII to relay 5WR. Accordingly, relays 5H and 5J pick up and cause the signal 5W to display its green or clear indication.

When the train advances into section 3T, the track relay 3TR releases and cuts off the supply of energy to the relay 4ER and the relays 4H and 4J release and condition the signal 4E to display its red or stop indication. Release of these relays also cuts off the supply of coded energy to the transformer XITT and effects the supply of steady energy thereto.

When the rear of the train vacates section 5T, track relay 5TR picks up and completes line circuit XII so that energy from the battery XIIB feeds to the relay 22ER. At this time relay 6ER is released as line circuit XI is interrupted by track relay 4TR so that relay 6H is released and its contacts 148 and 149 reverse the polarity of the energy supplied from the battery XIIB to line circuit XII. Accordingly, the polar contact 153 of relay 22ER is shifted to its reverse position to condition the signal 22E to display its yellow or caution indication. The circuit of the yellow lamp Y of signal 22E includes front contact 131 and reverse polar contact 153 of relay 22ER.

On picking up of the neutral contacts of relay 22ER contact 132 interrupts the supply of steady energy to the transformer XXITT and effects the supply of coded energy thereto so that coded energy is supplied to the relay 24ER and this relay follows code so that energy is supplied through the transformer 24DT to relay 24J. On picking up of the contacts of the relay 24J the aspect of signal 24E is changed from yellow or caution to green or clear, while a circuit including front contact 151 of relay 24J and front contact 128 of relay 24H is established to supply coded energy to the transformer XXITT and thus to the line circuit XXI so that the eastbound signal next in the west of signal 24E is conditioned to display its clear indication.

When the train advances into section 2T, the track relay 2TR releases and interrupts the line circuit X, but there is no change in the condition of the signals as this line circuit is already interrupted by track relay 3TR.

When the train vacates section 4T, track relay 4TR picks up so that energy from the battery XIIB is supplied over the line circuit XI to the relay 3WR. At this time relay 5H is picked up so that energy of normal relative polarity is supplied to the relay 3WR and this relay conditions signal 3W to display its green or clear indication.

As the train continues through the track stretch past siding Q, the signals associated with this siding operate in the same manner as the signals associated with siding P and their operation will not be traced in detail.

Operation of system on movement of a westbound train through the track stretch

For purposes of illustration it will be assumed that the track stretch is vacant and that a westbound train passes through the track stretch.

As the track stretch is vacant, the signals will be conditioned to display green or clear indications as explained in detail above.

When the westbound train enters section 1T, the track relay 1TR releases and interrupts line circuits IX and X. As line circuit IX is interrupted, relay 2ER is released and conditions

signal 2E to display its red or stop indication, while interruption of line circuit X by track relay 1TR cuts off the supply of energy from transformer XTT over line circuit X to relay 4ER. Relay 4ER, therefore, releases and relays 4H and 4J release and condition signal 4E to display its red or stop indication, while as contact 115 of relay 4H is released, coded energy is no longer supplied to the transformer XIITT and steady energy is supplied thereto.

On this change in the energy supplied to line circuit XI relay 6ER ceases to follow code and energy is not supplied through the transformer 6DT to the relay 6J. However, relay 6ER is steadily energized so that relay 6H is picked up and causes energy of normal relative polarity to be supplied from battery XIIB to line circuit XII, and to establish the circuit of the yellow lamp Y of signal 6E. This circuit includes front contact 145 of relay 6H and back contact 146 of relay 6J.

As energy of normal relative polarity is supplied over the line circuit XII to relay 22ER, this relay conditions signal 22E to display its green or clear indication, while neutral contact 132 of this relay is picked up and establishes the circuit for supplying coded energy to the transformer XXITT.

From the foregoing it will be seen that when a train is present in section 1T, signal 4E displays a stop indication, while signal 6E displays its yellow or caution indication. Accordingly, an eastbound train will receive ample warning of the approach of a westbound train and will be able to stop before colliding with the westbound train.

When the westbound train advances into section 2T, track relay 2TR releases and cuts off the supply of energy over line circuit X to relay 1WR and relay 1WR releases and conditions signal 1W to display its stop indication, while contact 103 releases and effects the supply of steady energy to transformer IXTT.

When the train advances into section 3T, the track relay 3TR releases and additionally interrupts line circuit X, but there is no change in the signals at this time.

When the train vacates section 1T, track relay 1TR picks up and energy is supplied over line circuit IX to relay 2ER and this relay causes signal 2E to display its green or clear indication, while contact 108 of this relay also establishes the circuit to supply coded energy to the transformer XTT.

When the train advances into section 4T, track relay 4TR releases and additionally interrupts line circuit X, while it also cuts off the supply of energy from battery XIIB over line circuit XI to relay 3WR and from transformer XITT to line circuit XI.

As a result of deenergization of relay 3WR, signal 3W displays its stop indication, while on cutting off of the supply of energy from the transformer XIITT to line circuit XI relay 6ER releases and relay 6H also releases so that signal 6E displays its stop indication. In addition, on release of relay 6H the polarity of the energy supplied from battery XIIB over line circuit XII to relay 22ER is changed from normal to reverse so that polar contact 153 of relay 22ER is shifted from its normal to its reverse position to thereby extinguish the green lamp G of signal 22E and establish the circuit of the yellow lamp Y of this signal.

When the rear of the train vacates section 2T,

track relay 2TR picks up, but line circuit X is interrupted by track relay 3TR so that there is no change in the signals at this time.

When the train advances into section 5T, track relay 5TR releases and interrupts the supply of energy from battery XIIB to line circuit XII so that relay 22ER is deenergized and its contact 131 establishes the circuit of the red or stop lamp R of signal 22E. In addition, on deenergization of relay 22ER its neutral contact 132 cuts off the supply of coded energy to the transformer XXTT and effects the supply of steady energy thereto. On this change in the energy supplied to the line circuit XX relay 24H is steadily picked up so that relay 24J remains picked up, while relay 24J releases so that the indication displayed by signal 24E is changed from green to yellow. Release of contact 151 of relay 24J interrupts the supply of coded energy to the transformer XXITT so that the eastbound signal next in the west of signal 24E is also conditioned to display its caution indication, and an eastbound train if approaching siding P would receive a yellow or caution indication at the signal next west of signal 24E, which would enable it to stop at signal 24E and enter siding P.

At this time coded energy from the transformer XIITT continues to feed to the relay 5WR so that relays 5H and 5J are picked up and condition signal 5W to display its green or clear indication.

When the rear of the train vacates section 3T, track relay 3TR picks up so that coded energy from the transformer XTT feeds to the relay 4ER and this relay supplies energy to the relays 4H and 4J to thereby cause signal 4E to display its green or clear indication. In addition, picking up of relays 4H and 4J effects the supply of coded energy to transformer XITT, but at this time line circuit XI is interrupted by track relay 4TR so that the coded energy does not feed to relay 6ER.

When the train advances into section 6T, track relay 6TR releases and cuts off the supply of energy from the transformer XIITT over line circuit XII to relay 5WR. This relay is, therefore, deenergized and relays 5H and 5J release and establish the circuit of the red or stop lamp R of signal 5W.

When the rear of the train vacates section 4T, track relay 4TR picks up so that energy from the battery XB is supplied to the line circuit X. At this time relay 3WR is deenergized so that its contacts 140 and 141 are released and the energy supplied from the battery XB to the line circuit X is of reverse polarity. Relay 1WR, therefore, is energized and its polar contacts 101 and 102 occupy their reverse positions. Accordingly, the circuit of the yellow lamp Y of signal 1W is established, while steady energy continues to be supplied to the transformer IXTT, and thus to the line circuit IX so that the westbound signal next to the east of signal 1W is conditioned to display its yellow or caution indication.

When the train advances into section 7T, track relay 7TR releases and additionally interrupts the line circuits XI and XII.

When the rear of the train vacates section 5T, track relay 5TR picks up, but at this time line circuits XI and XII are both interrupted by track relay 6TR so that picking up of track relay 5TR does not change the aspects of the signals.

When the train advances into section 21T, track relay 21TR releases and interrupts line circuit XX to cut off the supply of energy from the

transformer XXTT to relay 24ER. Relays 24H and 24J, therefore, release and condition signal 24E to display its stop indication, while release of these relays cuts off the supply of coded energy to the transformer XXITT and effects the supply of steady energy thereto with the result that the eastbound signal next in the west of signal 24E is caused to display its yellow or caution indication.

- 10 When the train vacates section 6T, track relay 6TR picks up so that coded energy from the transformer XIITT is supplied over the line circuit XI to relay 6ER, and this relay effects the supply of energy to the relays 6H and 6J so that they pick up and condition the signal 6E to display its green or clear indication.

When the train advances into section 22T, the track relay 22TR releases and cuts off the supply of energy from battery XXB to relay 21WR and this relay releases and conditions signal 21W to display its red or stop indication. In addition, release of relay 21WR cuts off the supply of coded energy to transformer XIITT and effects the supply of steady energy thereto. At this time, however, line circuit XII is interrupted by track relays 21TR and 7TR so that energy from the transformer XIITT does not reach relay 5WR and signal 5W continues to display its stop indication.

- 30 When the train vacates section 7T, track relay 7TR picks up so that energy from the battery XIIB is supplied over the line circuit XI to relay 3WR. This energy is of reverse relative polarity as the relay 5WR is deenergized and relay 5H is released. At this time, therefore, the polar contact 137 of relay 3WR is shifted to its reverse position and the signal 3W is caused to display its yellow or caution indication, while as the neutral contacts 140 and 141 of the relay 3WR are picked up, energy of normal relative polarity is supplied over line circuit X to relay 1WR and this relay conditions signal 1W to display its green indication. In addition, relay 1WR effects the supply of coded energy to the transformer IXTT so that coded energy is supplied over line circuit IX to thereby condition the westbound signal next in the east of 1W to display its green or clear indication.

When the train vacates section 21T, track relay 21TR picks up and energy from the battery XIIB feeds to the relay 22ER and this relay conditions signal 22E to provide its green or clear indication.

As the train proceeds through the track stretch, the signals associated with passing siding P operate in the same manner as the signals associated with section Q and a detailed explanation of their operation is not necessary.

From the foregoing it will be seen that on movement of a train through the track stretch in either direction the equipment operates to provide adequate protection to prevent a following train from running into the preceding train.

Thus, when an eastbound train is in section 23T or 22T associated with the passing siding P, the signal 24E displays its stop indication, while steady energy is supplied to the line circuit XX so that the eastbound signal next to the west of signal 24E displays its yellow or caution indication.

- 70 When an eastbound train is located in advance of signal 22E, this signal displays its stop indication, and steady energy is supplied to line circuit XX so that signal 24E displays its caution indication. In addition, the eastbound signal

next in the west also displays its caution indication so that a following train receives two caution indications and a stop indication before reaching the first train.

When an eastbound train is located in advance of signal 6E, this signal displays its stop indication, while line circuit XII is interrupted so that relay 22ER is released and conditions signal 22E to also display a stop indication. In addition, the two eastbound signals in the rear of signal 22E display yellow or caution indications.

When the train advances beyond track section 5T, signal 6E continues to display its stop indication, while signal 22E is conditioned to display its yellow or caution indication, and coded energy is supplied to the line circuit XX so that the eastbound signals in the rear of signal 22E display green or clear indications.

When the train advances beyond signal 4E, signal 4E displays its stop indication, while signal 6E displays its caution indication and signal 22E displays its clear indication.

It will be seen, therefore, that the first signal in the rear of an eastbound train displays a stop indication and also that there is at least one signal displaying a yellow or caution indication so that a following train has ample warning of the presence of the first train.

In like manner, protection is provided for westbound trains. When a westbound train is located in advance of signal 1W, this signal displays a stop indication, while steady energy is supplied to line circuit IX so that the adjacent westbound signal in the rear displays a caution indication.

When this train advances beyond signal 3W, this signal displays its stop indication, while signal 1W continues to display its stop indication until the train advances beyond section 4T at which time the aspect of signal 1W is changed from red to yellow.

When this train enters section 6T, signal 5W displays its stop indication, while signal 3W continues to display its stop indication until the train passes out of section 7T. When the train passes out of section 7T, signal 3W displays its yellow indication, while signal 5W continues to display its red or stop indication. The signals remain in this condition until the train enters section 22T. When this occurs, the signal 21W displays its stop indication, while when the train vacates section 21T, the indication displayed by signal 5W is changed from red to yellow, while that of signal 3W is changed from yellow to green or clear. The signal 5W continues to display its yellow or caution indication until the train vacates section 24T, at which time signal 23W displays its red or stop indication, while signal 21W displays its yellow or caution indication.

From the foregoing it will be seen that when a westbound train passes through the track stretch, the first westbound signal in the rear of the train will display a stop indication, while there is always at least one westbound signal in the rear of the train which displays a yellow or caution indication.

Operation of equipment on movement of trains in opposing directions through the track stretch

The equipment provided by this modification of the invention is arranged so that when a train moving in one direction passes through the track stretch, the signals in advance of the train and governing movement of traffic in the opposite direction are controlled far enough in advance of

the train to give a train moving in the opposite direction adequate warning and thereby prevent a head-on collision between trains.

When an eastbound train is present in section 24T at the left of passing siding P, signal 23W is at stop to thereby prevent a westbound train proceeding beyond the passing siding, while signal 21W is also at stop and signal 5W is at caution so that a westbound train has ample warning of the approach of the eastbound train.

When the eastbound train advances beyond passing siding P and enters section 21T, signal 5W is placed at stop, while signal 3W is placed at caution. As soon as the eastbound train enters section 7T, signal 3W is also placed at stop and signal 1W is placed at caution.

Similarly, when a westbound train is present in section 1T, the eastbound signal 2E is at stop, while the eastbound signal 4E is also at stop and the signal 6E is at caution.

When the westbound train proceeds beyond the passing siding Q and enters section 4T, the signal 6E is placed at stop, while signal 22E is placed at caution. As soon as the train enters section 5T, signal 22E is placed at stop and signal 24E is placed at caution, while the next eastbound signal to the west of signal 24E is also placed at caution. When the train advances into section 6T, signal 5W is placed at stop, while when the train advances into section 21T, signals 22E and 24E are both at stop and the eastbound signal next in the west of signal 24E remains at caution.

From the foregoing, it will be seen that this modification operates to provide an indication in advance of a train of the approach of the train so that trains moving in opposite directions will not collide head on.

It will be seen also that the modification shown in Fig. 3 like that shown in Fig. 1 has line circuits in which both alternating and direct current is employed and that one form of energy controls the signals for one direction of traffic and that the other form of energy controls the signals for the other direction of traffic.

The modification shown in Fig. 3 differs from that shown in Fig. 1 in that the two polarities of direct current are employed to provide two proceed indications, while coded and steady alternating current energy is employed to provide two proceed indications.

Although in this system alternating current energy of one code frequency together with steady alternating current energy is employed to provide the two proceed indications, the invention is not limited to this arrangement and it is contemplated that two code frequencies of alternating current might be employed to provide the two proceed indications.

Although I have herein shown and described only three forms of railway signaling systems embodying my invention, it is understood that various changes and modifications may be made therein within the scope of the appended claims without departing from the spirit and scope of my invention.

Having thus described my invention, what I claim is:

1. In combination, a stretch of railway track having a pair of track rails over which traffic moves in both directions, the rails of said track stretch being divided by insulated joints into a plurality of track sections including a first, a second, a third and a fourth track section, a first signal governing entrance of trains moving in

one direction into said second track section, a second signal governing entrance of trains moving in the other direction into the third track section, a pair of line conductors substantially coextensive with said second and third sections, means at the end of said conductors adjacent said first track section for supplying direct current to said conductors, means at the other end of said conductors for supplying alternating current to said conductors, a first and a second control device energized from said conductors, the first control device being responsive only to direct current and controlling said first signal, said device being operative when energized to condition said signal to display a clear indication and when deenergized to condition the signal to display a restrictive indication, the second control device being responsive only to alternating current and controlling said second signal, said second control device being operative when energized to condition said signal to display a clear indication and when deenergized to condition the signal to display a restrictive indication, means operative when said first section is occupied to interrupt the supply of alternating current to said line conductors while permitting direct current to be supplied over said conductors to the first control device, whereby when said first section is occupied and the other sections are vacant said first signal is conditioned to display its clear indication and the second signal is conditioned to display a restrictive indication, and means operative when said fourth section is occupied to interrupt the supply of direct current to said line conductors while permitting alternating current to be supplied over said conductors to the second control device, whereby when said fourth section is occupied and the other sections are vacant said second signal is conditioned to display its clear indication and the first signal is conditioned to display a restrictive indication.

2. In combination, a stretch of railway track having a pair of track rails over which traffic moves in both directions, the rails of said track stretch being divided by insulated joints into a first, an intermediate and a second track section, a first signal governing entrance of trains moving in one direction into said intermediate track section, a second signal governing entrance of trains moving in the other direction into said intermediate track section, a pair of line conductors substantially coextensive with said intermediate section, means at the end of said conductors adjacent said first track section for supplying direct current to said conductors, means at the other end of said line conductors for supplying alternating current to said conductors, a first and a second control device energized from said conductors, the first control device being responsive only to alternating current and controlling said first signal, said device being operative when energized to condition said signal to display a clear indication and when deenergized to condition the signal to display a restrictive indication, the second control device being responsive only to alternating current and controlling said second signal, said second control device being operative when energized to condition said signal to display a clear indication and when deenergized to condition the signal to display a restrictive indication, means operative when said first section is occupied to interrupt the supply of alternating current to said line conductors while permitting direct current to be supplied over said conductors to the first control device, whereby when said first section is occupied to interrupt the supply of alternating current to said line conductors while permitting direct current to be supplied over said conductors to the first control device, whereby

- when said first section is occupied and the other sections are vacant said first signal is conditioned to display its clear indication and the second signal is conditioned to display a restrictive indication, 5 and means operative when said second section is occupied to interrupt the supply of direct current to said line conductors while permitting alternating current to be supplied over said conductors to the second control device, 10 whereby when said second section is occupied and the other sections are vacant said second signal is conditioned to display its clear indication and the first signal is conditioned to display a restrictive indication.
- 15 3. In combination, a stretch of railway track having a pair of track rails over which traffic moves in both directions, the rails of said track stretch being divided by insulated joints into a first, an intermediate and a second track section, 20 a first signal governing entrance of trains moving in one direction into said intermediate track section, a second signal governing entrance of trains moving in the other direction into said intermediate track section, a pair of line conductors substantially coextensive with said intermediate section, means at the end of said conductors adjacent said first track section for supplying direct current to said conductors, means at the other end of said line conductors for supplying alternating current to said conductors, a first and a second control device energized from said conductors, the first control device being responsive only to alternating current and controlling said first signal, said device being operative when energized to condition said signal to display a clear indication and when deenergized to condition the signal to display a restrictive indication, the second control device being responsive only to alternating current and controlling 35 said second signal, said second control device being operative when energized to condition said signal to display a clear indication and when deenergized to condition the signal to display a restrictive indication, 40 means operative when said first section is occupied to interrupt the supply of alternating current to said line conductors while permitting direct current to be supplied over said conductors to the first control device, whereby when said first section is occupied and the other sections are vacant said first signal is conditioned to display its clear indication and the second signal is conditioned to display a restrictive indication, means operative when said second section is occupied to interrupt the supply of direct current to said line conductors while permitting alternating current to be supplied over said conductors to the second control device, whereby when said second section is occupied and the other sections are vacant said second signal is conditioned to display its clear indication and the first signal is conditioned to display a restrictive indication, 50 and means operative when said intermediate section is occupied to interrupt the circuit of said line conductors and thereby prevent the supply of energy to either of said control devices, whereby when said intermediate section is occupied said first and second signals are both conditioned to display restrictive indications.
- 55 4. In combination, a stretch of railway track having a pair of track rails over which traffic moves in both directions, the rails of said track stretch being divided by insulated joints into a plurality of track sections including a first, a second, a third and a fourth track section, a first 60
- 65
- 70
- 75

signal governing entrance of trains moving in one direction into said second track section, a second signal governing entrance of trains moving in the other direction into the third track section, a pair of line conductors substantially coextensive with said second and third sections, means at the end of said conductors adjacent said first track section for supplying direct current to said conductors, means at the other end of said conductors for supplying alternating current to said conductors, a first and a second control device energized from said conductors, the first control device being responsive only to direct current and controlling said first signal, said device being operative when energized to condition said signal to display a clear indication and when deenergized to condition the signal to display a restrictive indication, the second control device being responsive only to alternating current and controlling said second signal, said second control device being operative when energized to condition said signal to display a clear indication and when deenergized to condition the signal to display a restrictive indication, means operative when said first section is occupied to interrupt the supply of alternating current to said line conductors while permitting direct current to be supplied over said conductors to the first control device, whereby when said first section is occupied and the other sections are vacant said first signal is conditioned to display its clear indication and the second signal is conditioned to display a restrictive indication, means operative when said fourth section is occupied to interrupt the supply of direct current to said line conductors while permitting alternating current to be supplied over said conductors to the second control device, whereby when said fourth section is occupied and the other sections are vacant said second signal is conditioned to display its clear indication and the first signal is conditioned to display a restrictive indication, and means operative when either said second or third section is occupied to interrupt the circuit of said line conductors and thereby prevent the supply of energy to either of said control devices, whereby when either of said second or third sections is occupied said first and second signals are both conditioned to display restrictive indications.

5. In combination, a stretch of railway track having a pair of track rails over which traffic moves in both directions, the rails of said track stretch being divided by insulated joints into a first, an intermediate and a second track section, a first signal governing entrance of trains moving in one direction into said intermediate track section, a second signal governing entrance of trains moving in the other direction into said intermediate section, a pair of line conductors substantially coextensive with said intermediate section, a source of alternating current energy connected across the line conductors at the end thereof adjacent said first section, a source of direct current energy connected across the line conductors at the end thereof adjacent the second section, a first control device connected across said line conductors adjacent said source of alternating current, a second control device connected across said line conductors adjacent the source of direct current, the first control device being responsive only to direct current and the second control device being responsive only to alternating current, means operative on occupancy of said first section to interrupt connection of the source of

alternating current with said line conductors without interrupting connection of said first control device with said conductors, whereby when said first section is occupied and the other sections are vacant the second signal is conditioned to display a restrictive indication and the first signal is conditioned to display its clear indication, and means operative on occupancy of said second section to interrupt connection of the source of direct current with said line conductors without interrupting connection of said second control device with said line conductors, whereby when said second section is occupied and the other sections are vacant the first signal is conditioned to display a restrictive indication and the second signal is conditioned to display its clear indication.

6. In combination, a stretch of railway track having a pair of track rails over which traffic moves in both directions, the rails of said track stretch being divided by insulated joints into a first, an intermediate and a second track section, a first signal governing entrance of trains moving in one direction into said intermediate track section, a second signal governing entrance of trains moving in the other direction into said intermediate section, a pair of line conductors substantially coextensive with said intermediate section, a source of alternating current energy connected across the line conductors at the end thereof adjacent said first section, a source of direct current energy connected across the line conductors at the end thereof adjacent the second section, a first control device connected across said line conductors adjacent said source of alternating current, a second control device connected across said line conductors adjacent the source of direct current, the first control device being responsive only to direct current and the second control device being responsive only to alternating current, means operative on occupancy of said first section to interrupt connection of the source of alternating current with said line conductors without interrupting connection of said first control device with said conductors, whereby when said first section is occupied and the other sections are vacant the second signal is conditioned to display a restrictive indication and the first signal is conditioned to display its clear indication, means operative on occupancy of said second section to interrupt connection of the source of direct current with said line conductors without interrupting connection of said second control device with said conductors, whereby when said second section is occupied and the other sections are vacant the first signal is conditioned to display a restrictive indication and the second signal is conditioned to display its clear indication, and means operative when said intermediate section is occupied to interrupt the circuit of said line conductors and thereby interrupt the supply of energy to both of said control devices and thereby condition both of said signals to display restrictive indications.

7. In combination, a stretch of railway track having a pair of track rails over which traffic moves in both directions, the rails of said track stretch being divided by insulated joints into a first, an intermediate and a second track section, a pair of line conductors substantially coextensive with said intermediate section, means at the end of said conductors adjacent said first track section for supplying direct current to said conductors, means at the other end of said line con-

ductors for supplying alternating current to said conductors, a first semaphore signal governing movement of trains from said first track section into said intermediate section, a second semaphore signal governing movement of trains from said second track section into said intermediate section, each of said signals having a signal arm, a holding magnet and a motor, each signal arm being biased to a horizontal or stop position and being movable therefrom to a proceed position, each holding magnet having a pair of windings and being operable when either of said windings is energized to establish driving connection between the associated motor and signal arm and to also maintain the signal arm in its proceed position, each motor being operable when energized to move the associated signal arm from its horizontal to its proceed position, each signal having associated therewith a control relay operable when energized to establish a circuit to energize the signal motor and one winding of the signal holding magnet, the control relay and the other winding of the holding magnet associated with the first signal each being connected across the line conductors whereby said relay and said winding are supplied with energy over said line conductors from the source of direct current, the control relay and the other magnet winding associated with the second signal being connected across the line conductors through a rectifier and a transformer, whereby said relay and said magnet winding are supplied with energy over said line conductors from said alternating current source, the circuit of each control relay including contacts governed by the associated signal and closed in all positions of the signal except the proceed position thereof, means operative when said first section is occupied to interrupt the supply of alternating current to said line conductors while permitting direct current to be supplied over said conductors to the control relay and the holding magnet winding associated with the first signal, whereby when the first section is occupied and the other sections vacant said first signal is conditioned to provide a proceed indication and the second signal is conditioned to provide its stop indication, and means operative when said second section is occupied to interrupt the supply of direct current to said line conductors while permitting energy from the source of alternating current over the line conductors to the control relay and the holding magnet winding associated with said second signal, whereby when said second section is occupied and the other sections are vacant said second signal is conditioned to display a proceed indication and the first signal is conditioned to display its stop indication.

8. In combination, a section of railroad track, a pair of conductors governed by traffic conditions in said track section, means for supplying energy to said conductors, a semaphore signal governing movement of traffic in said track section, said signal having a signal arm, a holding magnet and a motor, said arm being biased to a horizontal or stop position and being movable therefrom to a proceed position, said holding magnet having a pair of windings and being operable when either of said windings is energized to establish driving connection between the signal motor and arm and to also maintain the signal arm in its proceed position, the motor being operable when energized to move the signal arm from its horizontal to its proceed position, a control relay operable when energized to estab-

lish a circuit to energize said motor and one winding of said holding magnet, and means for energizing said control relay and the other winding of said holding magnet with energy supplied over said conductors, the circuit for supplying energy from said conductors to the control relay including contacts which are governed by the signal arm and are closed in all positions of said arm except the proceed position thereof.

9. In combination, a stretch of railway track having a pair of track rails over which traffic moves in both directions, the rails of said track stretch being divided by insulated joints into a plurality of successive track sections including a first, an intermediate and a second track section, a pair of line conductors substantially coextensive with said intermediate track section, a first signal governing entrance of trains moving in one direction into said intermediate section, a second signal governing entrance of trains moving in the other direction into said intermediate section, each of said signals being capable of displaying a stop indication and a plurality of proceed indications, means governed by traffic conditions in said first section for supplying direct current to said conductors at the end thereof adjacent said first section, means governed by traffic conditions in said track stretch adjacent said first section and on the side of said first section remote from said intermediate section for at times causing the direct current supplied to said line conductors to be of a first character and at other times to be of a second character, means governed by traffic conditions in said second section for supplying alternating current to said conductors at the end thereof adjacent said second section, means governed by traffic conditions in said track stretch adjacent said second section and on the side of said second section remote from said intermediate section for at times causing the alternating current supplied to said line conductors to be of a first character and at other times to be of a second character, a first and a second control device energized from said conductors, the first control device being responsive only to alternating current and controlling said first signal, said first device being operative when deenergized to condition said first signal to display its stop indication and being operative according to the character of the energy supplied thereto to condition said signal to display one or another of its proceed indications, said second device being responsive only to direct current and controlling said second signal, said second device being operative when deenergized to condition said second signal to display its stop indication and being operative according to the character of the energy supplied thereto to condition said signal to display one or another of its proceed indications.

10. In combination, a stretch of railway track having a pair of track rails over which traffic moves in both directions, the rails of said track stretch being divided by insulated joints into a plurality of successive track sections including a first, an intermediate and a second track section, a pair of line conductors substantially coextensive with said intermediate track section, a first signal governing entrance of trains moving in one direction into said intermediate section, a second signal governing entrance of trains moving in the other direction into said intermediate section, each of said signals being capable of displaying a stop indication and a plurality of proceed indications, means governed by traffic

conditions in said first section for supplying direct current to said conductors at the end thereof adjacent said first section, means governed by traffic conditions in said track stretch adjacent said first section and on the side of said first section remote from said intermediate section for at times causing the direct current supplied to said line conductors to be of one polarity, means governed by traffic conditions in said second section for supplying alternating current to said conductors at the end thereof adjacent said second section and on the side of said second section remote from said intermediate section for at times causing the alternating current supplied to said line conductors to be continuous and at other times to be periodically interrupted, a first and a second control device energized from said conductors, the first control device being responsive only to alternating current and controlling said first signal, said first device being operative when deenergized to condition said first signal to display its stop indication and being operative according as steady or periodically interrupted energy is supplied thereto to condition said signal to display one or another of its proceed indications, said second device being responsive only to direct current and controlling said second signal, said second device being operative when deenergized to condition said second signal to display its stop indication and being operative according to the polarity of the energy supplied thereto to condition said signal to display one or another of its proceed indications.

11. In combination, a stretch of railway track having a pair of track rails over which traffic moves in both directions, the rails of said track stretch being divided by insulated joints into a

plurality of successive track sections including a first, an intermediate and a second section, a first line circuit substantially coextensive with said intermediate section, a second line circuit substantially coextensive with said intermediate section, a first signal governing entrance of trains moving in one direction into said intermediate section, a second signal governing entrance of trains moving in the other direction into said intermediate section, each of said signals being capable of displaying a stop indication and a plurality of different proceed indications, means governed by traffic conditions in said first section for supplying alternating current to the first line circuit at the end thereof adjacent the first section, means governed by traffic conditions in the track stretch adjacent said first section and on the side of said first section remote from the intermediate section for supplying alternating current to the second line circuit at the end thereof adjacent the first section, means governed by traffic conditions in said second section for supplying direct current to the first line circuit at the end thereof adjacent the second section, means governed by traffic conditions in the track stretch adjacent the second section and on the side of said section remote from said intermediate section for supplying direct current to the second line circuit at the end thereof adjacent the second section, a first and a second control means energized from said first line circuit, and a third and a fourth control means energized from said second line circuit, said first and third control means being responsive only to direct current and controlling said first signal, said second and fourth control means being responsive only to alternating current and controlling said second signal.

RALPH R. KEMMERER.
